CLAIM

The ornamental design for a fuel container, as shown and described.

DESCRIPTION

FIG. 1. is a left front perspective view of a fuel container of the present design;

FIG. 2 is a left side view thereof; and,

FIG. 3 is a right side view thereof.

The portions of the fuel container shown in broken lines form no part of the claimed design. The top, bottom, front and rear views for the design shown in FIGS. 1-3 have been omitted as those views are merely duplicative of other views of the design and include no surface ornamentation related to the design as claimed.
